UNITED STATES PATENT OFFICE.

JOSEPH S. BLATZER AND PHILIP J. PAWLOSKI, OF PONTIAC, MICHIGAN.

BOAT-PROPELLER.

1,089,391.

Specification of Letters Patent. Patented Mar. 10, 1914.

Application filed April 21, 1913. Serial No. 762,899.

To all whom it may concern:

Be it known that we, JOSEPH S. BLATZER and PHILIP J. PAWLOSKI, citizens of the United States, residing at Pontiac, county of 5 Oakland, State of Michigan, have invented a certain new and useful Improvement in Boat-Propellers, and declare the following to be a full, clear, and exact description of the same, such as will enable others skilled 10 in the art to which it pertains to make and use the same, reference being had to the accompanying drawings, which form a part of this specification.

This invention relates to propulsion of 15 boats and emergency stopping of boats by a powerful reverse propulsion. To stop the boat a plurality of side propellers are brought into reversing operation at the sides of the ship, so as to effect a gradual but early 20 stoppage of the boat in cases of emergency. These propellers may be also used to gradually slacken the speed of the boat in cases other than emergency when it is only desired to quickly control the boat. When 25 said side propellers are used with the main propeller turning to propel the boat forward they increase the speed of the boat.

In the drawings: Figure 1, is a horizontal, 30 longitudinal section of the hull of the ship, showing some of the side propellers in position for operation and some withdrawn out of position for operation. This figure is taken on the line B-B of Fig. 2. Fig. 2, is a section on the line A-A of Fig. 1.

35 *a*, represents the hull of the ship. Along the sides of the hull are a number of propeller wheel boxes *b* which may be formed as integral portions of the hull or may be fastened thereto in any water-tight joint. Each 40 of these boxes *b*, is open on its outside face and this opening is closed by a gate *c*, which is operated by air forced through the pipe *d*, to the cylinder *e*, where it raises the piston *f* which is connected to the gate *c* by the piston rod *g*. It will readily be understood that 45 when the compressed air is turned on, it will travel through the main pipe that leads into the feed pipes *d* and all the gates *c*, will be practically simultaneously raised. This will 50 allow of the shoving of the side propellers *h* out into the position shown by the dotted lines of Fig. 1. This is effected by a second set of cylinders *i*, which lie horizontally on the floor *j* of the hull. The air is let into 55 the feed pipes *k* through a main feed line and this forces the piston *l* from the po-

sition shown in Fig. 2, to an outward position. The piston rod *m* has a connection with the side-propeller shaft *z*, that allows that member to rotate relatively to the piston rod *m*. The clutch part *n* is fast to the shaft *z* and movement of the piston forces the clutch part *n* into engagement with the companion clutch part *p*, which is fast to a helical gear wheel *o* that ordinarily runs 60 loose upon the piston rod *m*. Each helical gear *o* meshes constantly with a worm gear *q* that is fast to one of the twin propeller shafts *r*, that run from the engines *s* to the main propeller wheels *t* of the boat.

It will readily be understood that when 70 the piston *l* is forced out by the application of the compressed air, the clutch will communicate the rotation of the main propeller shaft *r* to the side-propeller shaft *z*, which carries the side propeller *h*. This also 75 brings the side propeller *h* out of the side of the hull and it being rotated in the same direction as the main propeller shaft by the power from the engines, it will quickly stop 80 the boat when the engines have been reversed. The stoppage of the boat is effected very quickly by reason of the large resistance afforded to the water all along the hull by multiplying the number of side propellers. There are six shown in the drawings, 85 but it is obvious that any number may be used.

When it is desired to withdraw the side propellers *h* back into their boxes, the air 90 is sent through the feed pipes *u* and this will force the pistons *l* inward and both withdraw the side propellers *h* and also disengage the clutches *p* and *n*. The gates *c* are forced down to close the openings of 95 the boxes and make the side surfaces of the hull continuous by sending air through the feed pipes *x*. This forces the pistons *f* downward and closes the propeller wheel boxes. The necessary stuffing boxes are used 100 about the piston rods to prevent seepage of the water into the interior of the boat.

What we claim is:

1. The combination with a boat, having a plurality of propeller boxes along each 105 side, of a main propeller and shaft, a plurality of side propellers vertically disposed and ordinarily resting in said boxes, a plurality of cylinders and pistons, one cylinder and piston connected with each side 110 propeller, a means for furnishing compressed fluid to the pistons for forcing the

propellers outward, and driving connections on the said propellers and the main propeller shaft for interengaging when the said propellers are forced out by the said pistons and cylinders, substantially as described.

2. The combination with a boat, having a propeller box along each side, of means for driving the boat, a side propeller vertically disposed and ordinarily resting in each box, a gate for each box, apparatus operated by compressed fluid for substantially simultaneously raising the gates, apparatus operated by compressed fluid for thrusting the side propellers outward, and driving connections for connecting the side propellers with the means for driving the boat when the said apparatus thrusts the side propellers outward, substantially as described.

3. In combination with a boat provided with a plurality of propeller boxes along its sides, a main propeller and shaft driving the ship, a plurality of side propellers and

propeller shafts, one located in each box, a plurality of air cylinders, one for each side propeller, a piston in each air cylinder, a piston rod connected with each piston and having a connection with one side-propeller shaft, a clutch on the side-propeller shaft, one of the parts being fast to the shaft, the other part being free to rotate thereupon, a gear wheel fast to the last mentioned clutch part and constantly rotated by the main propeller shaft whereby the travel of the piston connects the side-propeller with the main propeller-shaft and thrusts the side-propeller out of the propeller-wheel box, substantially as described. 25 30 35

In testimony whereof, we sign this specification in the presence of two witnesses.

JOSEPH S. BLATZER.
PHILIP J. PAWLOSKI.
